COMBINATION LUGGAGE CARRIER

Eddy A. K. Stanger, Marysville, Ohio

Application October 14, 1931, Serial No. 568,806
Renewed June 14, 1933

6 Claims. (Cl. 45—51)

This invention relates to a combination device, the general object of this invention being to provide a device which can be converted into a luggage carrier, a garage creeper or shelf or a table with means whereby the device can be folded so that it will occupy but little space when not in use.

This invention also consists in certain other features of construction and in the combination 10 and arrangement of the several parts to be hereinafter fully described, illustrated in the accompanying drawings and specifically pointed out in the appended claims.

In describing the invention in detail, reference 15 will be had to the accompanying drawings wherein like characters denote like or corresponding parts throughout the several views, and in which:—

Figure 1 is a top plan view of one manner of carrying out the invention.

Fig. 2 is a section on line 2—2 of Fig. 1.

Fig. 3 is an end view showing the device used as a creeper.

Fig. 4 is a top plan view showing the inner frame 25 in tilted position in the outer frame and with the top member removed.

Fig. 5 is an end view showing how the creeper member can be adjusted to various positions in the outer frame.

Fig. 6 is a view of the device used as a table.

Fig. 7 is a section on the line 7—7 Fig. 1.

Fig. 8 is a section on line 8—8 of Fig. 1.

Fig. 9 is a section on line 9—9 of Fig. 1.

Fig. 10 is a top plan view showing the device 35 connected with a pair of brackets.

Fig. 11 is an edge view of Fig. 10.

Fig. 12 is an end view.

Fig. 13 is a view showing clips for holding the table cloth or the like to the table shown in Fig. 6.

In the drawings, the numeral 1 indicates an 40 outer frame, the end portions of which are formed with the offset parts 2 to carry the bolts 3 located in the slots 4 and having thumb nuts 5 at their outer ends for engaging the brace rods 6, shown in Figs. 10, 11 and 12, when the frame is pivotally connected with the brackets 8, the braces being connected with the brackets as shown at 9 in a detachable manner. Each 45 brace is provided with the fastening part 10 for engaging part of the bracket when the braces are not in use. It will of course be understood that the brackets are to be connected to a wall as shown in Fig. 12, so that the device can be used as a shelf. When desired the device can 50 be dropped into vertical position by releasing

the ends of the braces from the parts at the lower ends of the brackets.

Other brackets can be used for supporting the device from a motor vehicle or the like, so that the device can be used as a luggage or trunk 60 carrier, it being understood that the brackets must be of a shape to permit them to be attached to a part of the vehicle. An inner frame 11 is pivotally supported in the outer frame by the central rod 12 which passes through the center portion of the two frames and has nuts 13 at its ends so that by removing one or both of these nuts and pulling the rod out of the frame, the two frames can be separated.

A metal top forming member 14 is adapted to 70 fit into the inner frame and to rest upon the rods 15 carried by the frame as shown in Fig. 2, said top member being provided with slots 16. The inner frame can be held in the last-mentioned outer frame by threading the eye 75 screws 17 in the side members of the outer frame into holes 18 in the side members of the inner frame, and the central eye bolts 17' also serves the purpose of holding the hinged legs 19 carried by the member 14 in folded position by having the inner ends of the set screws or bolts engaging the ends of the legs when the same has been folded into overlapping relation.

Braces 20 hold the legs in vertical position as 80 shown in Fig. 9. The inner construction formed by the inner frame 11 and the top part 14 also carries the castors 21 of any desired or suitable construction so that the device can be used as a garage creeper, as well as a table, a luggage carrier, or a shelf.

When the device is used as a luggage carrier, ropes or straps can be passed through the eye bolts 17 and 17' or the side members of the outer frame can be formed with the loops 22 to receive such cables or straps which pass over the 95 luggage placed on the device.

The member 14 is formed with a pair of holes 23 at each end thereof for receiving pins on a head rest 24 and by providing a pair of holes 100 at each end of the member 14, the head rest can be placed on either end thereof. Also by pivoting the inner frame in the outer frame by the rod 12, the parts can be rotated so that the plain part of the member 14 will be visible with 105 the folded legs, or the caster wheels, and the head rest on the inner face thereof hidden from view.

Fig. 13 shows clips 25 of spring metal which are adapted for use in holding a table cloth or 110 the like on the table shown in Fig. 6.

It is thought from the foregoing description that the advantages and novel features of the invention will be readily apparent.

It is to be understood that changes may be made in the construction and in the combination and arrangement of the several parts provided that such changes fall within the scope of the appended claims.

Having thus described my invention, what I claim as new is:—

1. A device of the class described comprising a frame, having outwardly offset portions on its end parts adjacent the front of the frame and said portions having elongated slots therein, bolts passing thru the slots, brackets pivoted to the rear part of the frame and brace members pivoted to the brackets and having openings at their outer ends for receiving the bolts.

2. A device of the class described comprising a frame, having outwardly offset portions on its end parts engaging the front of the frame and said portions having elongated slots therein, bolts passing through the slots, brackets pivoted to the rear part of the frame and brace members pivoted to the brackets and having openings at their outer ends for receiving the bolts, an inner frame fitting in the first-mentioned frame, a rod passing longitudinally through the central portions of the frames for pivoting the inner frame in the first frame, means for removably holding the rod in position, and means for holding the inner frame in alignment with the outer frame.

3. A device of the class described comprising a frame, having outwardly offset portions on its end parts adjacent the front of the frame and said portions having elongated slots therein, bolts passing through the slots, brackets pivoted to the rear part of the frame and brace members pivoted to the brackets and having openings at their outer ends for receiving the bolts, an inner frame fitting in the first-mentioned frame, a rod passing longitudinally through the central portions of the frames for pivoting the inner frame in the first frame, means for removably holding the rod in position, means for holding the inner frame in alignment with the outer frame, said means including eye bolts threaded in portions of the outer frame, and engaging parts of the inner frame.

4. A device of the class described comprising a frame, having outwardly offset portions on its

end parts adjacent the front of the frame and said portions having elongated slots therein, bolts passing through the slots, brackets pivoted to the rear part of the frame and brace members pivoted to the brackets and having openings at their outer ends for receiving the bolts, an inner frame fitting in the first-mentioned frame, a rod passing longitudinally through the central portions of the frames for pivoting the inner frame in the first frame, means for removably holding the rod in position, and means for holding the inner frame in alignment with the outer frame, spaced bars extending longitudinally in the inner frame, and a cover member fitting in the inner frame and engaging said bars.

5. A device of the class described comprising an outer frame, an inner frame fitting in the outer frame, a rod passing longitudinally through the central portions of the two frames for pivoting the inner frame in the outer frame, means for removably holding the rod in position, brackets detachably and pivotally connected to the rear part of the outer frame, brace members pivoted to the brackets, bolts connecting the outer ends of the brace members to the front portions of the outer frame, bolts passing through portions of the inner and outer frames for holding said frames in alignment, a cover member fitting in the inner frame, members each having one end pivoted in a corner of the cover member, each pair of members extending along an under side edge of the cover member and having their inner ends overlapping and held in position by said last mentioned bolts.

6. A device of the class described comprising an outer frame, an inner frame fitting in the outer frame, a rod passing longitudinally through the central portions of the two frames for pivoting the inner frame in the outer frame, means for removably holding the rod in position, brackets detachably and pivotally connected to the rear part of the outer frame, brace members pivoted to the brackets, bolts connecting the outer ends of the brace members to the front portions of the outer frame, bolts passing through portions of the inner and outer frames for holding said frames in alignment, a cover member fitting in the inner frame, and projections carried by the cover member and extending below the frames.
